UNITED STATES PATENT OFFICE.

ELI HORN AND ELMORE SHERMAN, OF LOUISVILLE, KENTUCKY.

MACHINE FOR INSERTING SHELL CORKS IN BOTTLES.

1,125,326.

Specification of Letters Patent.

Patented Jan. 19, 1915.

Application filed November 17, 1913. Serial No. 801,469.

To all whom it may concern:

Be it known that we, ELI HORN and ELMORE SHERMAN, citizens of the United States, residing at Louisville, in the county of Jefferson and State of Kentucky, have invented a new and useful Machine for Inserting Shell Corks in Bottles, of which the following is a specification.

This invention relates to machines for inserting shell corks in bottles, and an object is to provide means that will automatically arrange the corks and deliver them to inserting means, in proper position for insertion.

With the foregoing, and other objects in view, our invention consists of the novel construction and arrangement of parts to be hereinafter referred to, and more specifically pointed out in the claims appended hereunto.

Referring now in detail to that embodiment of our invention illustrated in the accompanying drawings wherein like reference characters indicate like parts in the different views, Figure 1, is a front elevation of our machine, with parts broken away and some omitted to better show the construction. Fig. 2, is a side elevation, parts being broken away. Fig. 3, is a rear elevation. Fig. 4, is a transverse section through the hopper on the line $\alpha-\alpha$ of Fig. 3. Fig. 5, is a perspective of the shell cork used. Fig. 6, is a perspective of the cork-holder.

Referring more specifically to the drawings —1— designates a frame comprising legs —2— and a top —3—; on the top are disposed longitudinal guide strips —4—. Vertical standards —5— are mounted to slide in bearings —6—, secured on the side of the frame. The standards 5 may be raised and lowered by use of a hand lever —7—, secured on a shaft —8—, through the medium of arms —9— and links —10—. Near the upper ends of the standards a transverse bar —11— is adjustably secured and serves to rigidly connect the standards. A plurality of plungers —12— are positioned on the bar 11, the lower end of each plunger 1 is provided with a teat —13—, the purpose of which will be made evident hereinafter; the lower end of the plunger above the teat 13, is provided with a section —14— of a suitable cushioning material, such as leather, rubber or other substance of yielding nature, to prevent the chipping of the mouths of bottles should the plunger contact

therewith. A sliding bearing —15— is mounted on each of the standards 5, and upheld in a given position thereon by set collars —16—. A cross-bar —17—, preferably angular in cross section, is secured by suitable means to the bearings 15, rigidly connecting them; and so positioned, slightly in advance of the standards, that cork-holders —18— mounted thereon will have their axes in alinement with those of the plungers 12. The cork-holders 18 each comprise a cylindrical body, the bore of which will permit the passage of a cork, and a radial boss —20— projecting from the lower section 60 having a stem —21— extending in a prolongation of its axis. The upper section is divided longitudinally, one half —22— being integral with the lower section, and the other half —22— hinged at —23— to the 65 integral portion, forming what may be termed a lid. A spring —24— coiled around the pintle of the hinge serves to hold the lid normally closed. From the upper member of the lid an arm —25— extends, on the end 70 of which is a roller —26—. A shield —27— extends tangentially from the side opposite the hinges and away from the lid. On the lower end of the body portion is a cone-shaped hood —28—. The cork-holders are mounted 75 on the cross-bar 17 by passing the stems 21 through the bearings —29— thereon, the face of the boss 20 bearing against the face of the bearing, the cork-holders being held 80 in place by means of arms —30— secured 85 on the end of the stem. The arms 30 are secured on the stems in such relationship to the cork-holders that the arms are at an angle of 45° to the right of the vertical 90 when the cork-holders are in a horizontal 95 position (the position in which corks are received). The arms 30 are connected by a rod —31—, that in turn is connected by a link —32— with an arm —33— pivoted on a bracket —34— depending from the cross-bar 17. On the arm 33 is a roller —35— that engages in a cam-slide —36—, attached to and extending up from the frame 1. The arrangement being such that as the standards, and associated elements, descend the 100 roller 35 will enter the cam-slide and shift the arm 33 and connected arms 30 to the left far enough to turn the cork-holders to a vertical position. A hopper —39— is supported in the rear of and elevated above 105 the cross-bar by means of braces —40, 41—. The hopper is provided with a plurality of

compartments —42— each having inclined walls converging to exit —43— in the bottom thereof, through which corks —44— may pass into chutes —45—. The chutes being arranged therebelow at an angle that will allow the corks to roll down freely by gravity, the chutes terminating at a point to deposit corks in the cork-holders 18. The length of the exit is sufficient to accommodate several corks, the width however is but slightly greater than the length of the cork, the arrangement being such that corks can only pass through when the ends thereof lie in vertical planes parallel with the sides of the exits. The front and side walls of the compartments are plane surfaces, but the rear wall is curved forward, with the convex surface within the compartment, in order to provide room for an agitator shaft —46— that is journaled in the end walls —47— of the hopper. On the shaft 46 are a plurality of hubs —48—, disposed in alignment with the exits, a plurality of fingers —49— project from each of the hubs and pass upward through the exits as the shaft is turned, slots —50, 51—, in the bottom of the chute and in the rear wall of the hopper, respectively, provided for the passage of the fingers. On the outer end of the shaft 46 is a disk —52— having a plurality of pins —53— projecting from the face thereof. A vertical stem —54—, attached to the frame at —55—, carries at the top thereof a plate —56— that lies between the disk 52 and the end 47 of the hopper, the plate is provided with a vertical slot —57— that embraces the shaft 46, allowing vertical movement of the shaft therein and holding the plate 56 in vertical alignment.

Arranged on the face of the plate are oppositely disposed pawls—58, 59—, the arrangement being such that as the hopper descends a pin on the disk will engage with the pawl 58, and the disk, with associated members, will receive a quarter turn, and as the hopper returns, another pin will engage the pawl 59 and the disk will receive another quarter turn, in the same direction.

In operating the machine a quantity of shell corks are dumped in the hopper, and as they fall to the bottom thereof some will be in position to pass through the exits 43, and roll down the chutes, others will fall across the exits (as shown in Fig. 3) obstructing it. A forward movement of the operating lever 7 will cause a finger 49 to pass upward through each exit (as previously explained) raising the obstructing corks and allowing them to fall back, when some may pass through the exit and others again obstruct it, as the lever is raised the corks will again be raised from off the exit, and as they fall back some will pass through while others will fall across it. It will be observed that this agitation of the corks

occurs twice each time the hopper is raised and lowered. By manipulating the lever 7 a few times the chutes may be filled with corks, bottles may then be placed in position and corking commenced. If the parts are in the upper, or normal position of rest, the first cork that rolls down the chute will fall into the cork-holder 18, the receiving chamber of which lies open just at the end of the chute, succeeding corks will accumulate in the chute. Bottles that are to be corked are placed on the table between the guide strips 4, with their mouths in approximate alignment with the plungers 12. The lever 7 is then manipulated to lower the standards 80 and associated elements, as the cross-bar 17 descends the roller 35 enters the cam slide 36 shifting the cork-holders, and contained corks, to a vertical position in which the corks are delivered to the bottles, as the cork-holders assume a vertical position the outlet of the chutes are closed by the shields 27, preventing the escape of corks therefrom. The cross bar descends until the hoods encounter and center the bottles, it then rests on the bottles, its travel being intercepted thereby. The continued downward movement of the standards brings the plungers into contact with the corks, in the holders, forcing them therethrough into the bottles, 95 the teats 13 on the plungers enter the bore of the corks before the body of the plunger encounters the end of the cork and applies pressure thereto, this prevents splitting of the corks. As the lever 7 is raised, the plungers are withdrawn from the cork-holders, the roller 35 enters the cam-slide 36, returning the cork-holders to a horizontal position. As the cork-holders return to the horizontal position the rollers 26 strike a cam projection —61—, on the cross-bar 17, raising the lids 22.

It is thought that the many advantages of a corking machine constructed in accordance with the foregoing description can be readily understood, and it will furthermore be evident that changes, variations, and modifications can be resorted to without departing from the spirit of the invention or sacrificing any of its advantages, and we therefore do not wish to restrict ourselves to the details of construction hereinbefore described and as shown in the accompanying drawings, but reserve the right to make such changes, variations, and modifications as come properly within the scope of the protection prayed.

Having thus described our invention so that any one skilled in the art pertaining thereto may make and use the same we claim:

1. In a machine of character described, an oscillatory holder for corks adapted, in a horizontal position, to receive corks and in a vertical position to discharge them, means

for feeding corks to said holder and means for turning said holder from one position to the other.

2. In a machine of the character described, a stand, movable standards thereon, upper and lower cross-bars on said standards, said upper cross-bar being rigidly attached to said standards, said lower cross-bar movable relative to said standards, 10 plungers mounted on said upper cross-bar, a hopper carried by the lower cross-bar, cork holders mounted on the lower cross-bar, chutes leading from the hopper to the cork-holders, said cork-holders adapted, in one 15 position to receive corks, and to be shifted into another position to allow the corks to be discharged.

3. In a machine of the class described, the combination of upper and lower cross-bars, plungers mounted on the upper cross-bar, hoppers carried by the lower cross-bar, oscillating cork-holders mounted on the lower cross-bar and adapted when in a horizontal position to receive corks, and means 25 to turn said holders into a vertical position to bring the corks to a point beneath the plungers.

4. In a machine of the class described, a stand, movable standards thereon, a plurality of plungers carried thereby, a cross-bar mounted on said standards and movable relative thereto, a hopper carried by said cross-bar, said hopper provided with exits that permit the passage of corks only when the 35 ends of the corks lie in vertical planes parallel with the sides of the exits, cork-carriers mounted on said cross-bar and adapted to receive corks when in a horizontal position, means for turning said carriers to a vertical position to bring the corks under the plungers, and means for holding the corks in said carrier.

5. In a machine of the class described, a stand, movable standards thereon, a plurality of plungers carried by said standards, a cross-bar mounted on said standards and movable relative thereto, a hopper carried by said cross-bar, cork-carriers mounted on said cross-bar, exits in said hopper, chutes 50 leading from the exits to the cork-carriers, closures for said carriers adapted to be opened as said carriers assume a position to receive corks, means to close said closures as the carriers leave said position, means for moving said carriers to bring the corks under the plungers.

6. In a machine of the class described, in combination, a stand, standards mounted on and movable relative thereto, a cross-bar 60 mounted on said standards and movable relative thereto, a hopper carried by said cross-bar, said hopper having a plurality of compartments each having inclined walls and an exit in the bottom thereof, means for agitating corks in said hopper, chutes leading

from the exits, cork-carriers mounted on said bar in a position normally to receive corks from said chutes, means for shifting said carriers, and means associated with said carriers for closing the outlets from 70 the chutes.

7. In a machine of the character described, an oscillatory cork carrier, a closure on the side thereof, means for operating said closure, and means for oscillating said carrier.

8. In a machine of the character described, a stand, movable standards carried thereby, a cross-bar mounted on said standards, cork-carriers mounted on said cross-bar, closures for said carriers, means associated with said bar for operating said closures, and means associated with said stand for shifting the position of the carriers.

9. In a machine of the character described, a stand, movable standards carried thereby, upper and lower cross-bars, a plurality of plungers carried by the upper bar, said lower bar movable relative to said standards, a hopper carried by the lower bar, said hopper having exits in the bottom thereof, chutes leading from said exits, said exits adapted to permit the passage of corks only in a position to roll down said chutes, cork-carriers mounted on said lower bar, 95 closures for said carriers, means for opening said closures as the carriers assume a position to receive corks from the chutes, means associated with the stand to shift the carriers to bring the corks under the plungers. 100

10. In a machine of the character described, an oscillatory cork-carrier, a lid hinged on the side thereof, means tending normally to close said lid, means for opening said lid as the carrier assumes a recipient position, and means for oscillating the carrier.

11. In a machine of the character described, an oscillatory cork-carrier, means for delivering corks thereto when the same is in a horizontal position, means for turning said carrier into a vertical position, and means for discharging corks therefrom while in said vertical position.

12. In a machine of the class described, in combination, bottle-supporting means, standards movable relative thereto, a cross-bar slidably mounted on said standards and adapted to travel therewith until arrested by contacting with bottles carried by said support, cork-carriers mounted on said bar, means for feeding corks to said carriers, plungers rigidly connected with said standards and adapted to enter said carriers and force corks therefrom into the bottles.

13. In a machine of the class described, in combination, bottle-supporting means, standards movable relative to said supporting means, cork-carriers mounted on said bar, means for supplying corks to said car- 130

- riars, means for turning said carriers from a receiving to a delivering position, said cross-bar adapted to travel with said standards until arrested by the carriers contacting 5 with bottles carried by said supporting means, a bar rigidly attached to said standards, plungers depending from said rigid-bar and adapted to enter said carriers and drive corks therefrom.
- 10 14. In a machine of the class described, in combination, a stand, movable standards carried thereby, a cross-bar slidably mounted on said standards, hoppers carried by said bar, a shaft mounted below said hoppers, fingers extended from said shaft into the hoppers, a disk on the end of the shaft, pins projecting from the face of said disk, a vertical stem extended up from the stand, a plate on the upper end of the stem, and 20 pawls on said plate adapted to engage with said pins and turn the shaft.
- 15 15. In a machine of the class described, in combination, a stand, movable standards carried thereby, a cross-bar slidably mounted on said standards, transverse bearings on said bar, tubular cork-carriers, radial stems on said carriers extended through said bearings, crank-arms on the ends of said stems, a rod connecting said crank-arms, and

means extended up from the stand to engage 30 and shift said rod to turn said carriers.

16. In a machine of the class described, a stand, standards movably mounted thereon, a cross-bar slidably mounted on said standards, transverse bearings on said bar, 35 tubular cork-carriers, radial stems on said carriers extended through said bearings, means for turning said carriers in said bearings, lids on the sides of said carriers, springs adapted to close said lids, cam projections on the bar adapted to open said lids as the carriers assume a horizontal position to receive corks.

17. In a machine of the class described, a stand, movable standards thereon, a lower 45 cross-bar slidably mounted on said standards, an upper cross-bar rigidly mounted on the standards, cork-handling means carried by said lower bar, plungers carried by said upper bar, reduced axial extensions on said 50 plungers, and cushion members on the ends of said plungers above said extensions.

ELI HORN.
